CLAIM

The ornamental design for a case for an electronic tablet, as shown and described.

DESCRIPTION

FIG. 1 shows a perspective view of a design of case for an electronic tablet.

FIG. 2 shows a top view of the design.

FIG. 3 shows a bottom view of the design.

FIG. 4 shows a left side view of the design folded into a first stand position in use with an electronic tablet; and,

FIG. 5 shows a back perspective view of the design folded into a second stand position in use with an electronic tablet. The broken lines depict environmental subject matter and form no part of the claim.
